UNITED STATES PATENT OFFICE.

CHARLES DUNNING, OF NEW ORLEANS, LOUISIANA.

JOURNAL-BEARING.

1,085,853.

Specification of Letters Patent.

Patented Feb. 3, 1914.

Application filed January 20, 1913. Serial No. 743,127.

To all whom it may concern:

Be it known that I, CHARLES DUNNING, a citizen of the United States, residing at New Orleans, in the parish of Orleans and

5 State of Louisiana, have invented certain new and useful Improvements in Journal-Bearings, of which the following is a specification, reference being had to the accompanying drawings.

10 This invention relates to new and useful improvements in journal bearings for railway cars and the like, the object of the invention being to provide a simple and practical divergent roller bearing which may be 15 readily substituted for the ordinary bearings now in general use on steam and electric railway cars, street cars and similar vehicles.

Another object of the invention is to provide 20 a bearing of this character which will possess advantages in points of efficiency and durability, is inexpensive of manufacture and at the same time is simple in construction and operation.

25 With the above and other objects in view, the invention consists in the novel features of construction and the combination and arrangement of parts hereinafter more fully described, pointed out in the claim and 30 shown in the accompanying drawings, in which—

Figure 1 is a side elevation of a journal bearing constructed in accordance with my invention. Fig. 2 is a longitudinal sectional view taken on line 2—2 of Fig. 4. Fig. 3 is a transverse sectional view taken on the 35 line 3—3 of Fig. 1. Fig. 4 is an end elevation.

My improved journal bearing comprises 40 a body 1 which is preferably similar in size and shape to the ordinary journal now in use so that it may be readily substituted for the same, and it is composed of two sections 2 and 3, the latter of which is adapted 45 to fit in a recess 4 in one end of the former and to be retained therein by a screw, bolt or similar fastening 5. Formed in the bottom of the body 1 is the usual semi-cylindrical recess 6 adapted to receive the journal 50 or axle, but the latter instead of contacting the wall of said recess is engaged by the anti-friction rollers 7 arranged in cylindrical cavities 8 formed in the inner portion of the section 2 and having portions in communication with the recess 6 so that the pe-

ripheries of said rollers project into the latter as clearly shown in Fig. 3.

At the ends of the rollers 7 are reduced trunnions 9 and 10, the former of which are disposed in openings 11 formed in the closed end of the section 2 concentric with the cavities 8. The other trunnions 10 are arranged in similar openings 12 formed in the other section 3, which latter, as above stated, is removably arranged in the recess 4 so as to permit of the insertion of the rollers 7 in the cavities 8 and of their removal therefrom. It will be noticed that the recess 4 is in the form of a transverse channel extending across one end of the section 2 of the body and that the section 3 closes the open ends of the cavities 8. When the section 3 is in position and secured by the screw 5, its openings are concentric with the cavities 8.

Threaded in the openings 11 and 12 are the sleeves 13 which are provided upon the interior thereof with the annular raceways 14 adapted to receive annular series of anti-friction bearing balls 15 which latter engage the trunnions 9 and 10 as shown more clearly in Fig. 2 of the drawings. The outer ends of each of the sleeves 13 are provided with an annular flange 16 which is further provided at diametrically opposite points with recesses 17 adapted to receive the engaging portions of an especially constructed wrench whereby the sleeves may be readily placed in or removed from the openings. Arranged between the openings 11 and 12 at each end of the body is a substantially rectangular key member 18 having reduced ends 19 projecting longitudinally thereof and adapted to engage within the recesses 17 when the sleeves are in position 50 to prevent any rotary movement thereof so that the same will not become displaced from within the openings 8.

Hingedly secured to one side of the annular flange 16 are the dust proof doors 20 which, when the sleeves are in position, are adapted to be secured down over the outer ends thereof to prevent any dust or any other foreign particles from entering the same. The rollers 7 and trunnions 9 and 10 are provided with a centrally arranged longitudinal opening 21 closed at one end and provided at the other end with a spring held cap whereby the same may be readily filled with oil or other lubricant, said open-

ing forming a suitable receptacle for retaining the oil within the rollers. The trunnions 9 and 10 are each provided with an opening 20' adapted to communicate with the longitudinal opening 21 so as to permit a continuous flow of oil into the sleeves 13, said flow being sufficient to lubricate the bearing balls 15. Provision is made in this journal ball bearing to oil the bearings, 10 which will prevent rusting, but otherwise it is not requisite to use oil on the balls, as it is an anti-friction device. Coagulation of dust or other particles in the ball pockets is enhanced by the application of oil. Therefore, 15 it is altogether optional whether or not to use oil.

From the foregoing description taken in connection with the accompanying drawings, it will be readily apparent that my improved bearing may be quickly and easily substituted for one of the ordinary journal bearings now in use upon railway cars and the like and that it will prevent friction and last much longer than the ordinary 20 journal bearings. It will be noted that in the event of the roller breaking, there will be no material damage resulting, because the shape of the recess 6 is such as to serve as a bearing surface for the journal or axle. 25 It will be apparent that the bearing balls 15 and the sleeves 13 may be readily removed from the openings 11 and 12 for cleaning purposes without removing the rollers 7.

While I have shown and described the 30 preferred form of my invention, it will be obvious that various changes in the details

of construction and in the proportions may be resorted to for successfully carrying my invention into practice without sacrificing any of the novel features or departing from 40 the scope of the appended claim.

What I claim is:—

In a journal bearing, the combination with a body having one section formed with a recess to receive the journal and with communicating cavities open at one end, a separate section adapted to close the open ends of said cavities, antifriction rollers arranged in said cavities and having their peripheries projecting into the journal receiving recesses, said sections having openings concentric with said cavities, of sleeves removably arranged in said openings to receive the trunnions of said rollers, said sleeves being provided upon the interior thereof with 45 annular raceways, bearing balls arranged within said raceways and adapted to engage the trunnions of the rollers, an annular flange formed upon one end of said sleeves, having oppositely disposed recesses formed 50 therein, key members secured to each end of the body and disposed between said sleeves, reduced end portions formed upon said key members and adapted to engage within said recesses to prevent the rotary movement of 55 said sleeves.

In testimony whereof I hereunto affix my signature in the presence of two witnesses.

CHARLES DUNNING.
